UNITED STATES PATENT OFFICE.

ETTORE BELLINI, OF PARIS, FRANCE.

RADIOGONIOMETER.

Application filed October 31, 1925, Serial No. 66,119, and in France November 20, 1924.

My invention relates to radio-goniometers employing fixed loops and one of the objects of the invention is to provide a radio-goniometer employing two fixed loops which may be tuned.

Another object of my invention is to provide a compact type of radio-goniometers which may be used in aeroplanes.

Other objects and advantages of my invention will appear more fully as herein-after set forth and as illustrated in the appended drawing.

Referring to the drawing, Fig. 1, is a diagrammatic sketch showing an aeroplane in the two wings of which the loops of the radio-goniometers are attached. Fig. 2, shows an arrangement, wherein the bridge circuit is tuned by means of a series of condensers.

Figs. 3, and 4, show arrangements wherein a bridge circuit may be coupled to toroidal inductances whereby the coils in the diametrically opposed quadrants of the toroidal windings further tend to diminish any effects of inequalities in the four condensers. Figure 5 is a diagrammatic representation of the uni-control arrangement of the tuning means.

In the old type of Bellini-Tosi receiving radio-goniometers similar perpendicular loops or coils connected in series with a radio-goniometer (properly so called) were used.

The tuning of the two coils was effected by the aid of variable condensers inserted in the middle of the above mentioned fixed and mechanically connected coils. The two condensers evidently were never identical, but the degree of similarity obtainable was practically sufficient at the period when crystal detectors and damped waves were used.

With the adoption and introduction of continuous wave and vacuum-tube amplifiers the situation changed entirely. The two more or less similar condensers proved no longer adequate. The points or zero signal strength disappeared, while at minimum signal strength values the taking of bearings became impossible owing to obscure and indistinct reception. The explanation for this situation is as follows:

In a continuous wave system of radio-communication, small differences in the capacity of the two condensers were more than sufficient for producing large differences in the phases of the strength of the

currents in the two aerials, which resulted in forming a revolving magnetic field inside the radio-goniometer. Therefore, no matter what the position of the mobile coil may be, the zero position of signal strength could never be obtained. This inconvenience was still more aggravated when using amplifiers by means of which the sensitivity of the circuits and their tendency to magnify defects in reception existed. The remedies suggested to benefit the above serious drawbacks were as follows:

First, to make the two tuning condensers independent of one another with a view to tuning the loops separately one after the other.

Second, to add a small equalizing condenser in parallel with that of the variable condensers which showed the lowest capacity.

Neither of these two remedies proved satisfactory.

Aperiodic loops were next experimented with, that is, they were connected with the coils of the radio-goniometer without the insertion of condensers. This method gives good results for wave lengths above 2,000 meters, while for shorter waves the loss of sensitivity is so great that in order to compensate for this loss it is necessary to provide amplifiers which often comprise a great number of tubes.

Since the sensitivity of amplifiers made it possible to use small revolving loops or coils as radio-goniometers interest in the problem diminished considerably,—to such a degree, was this the case that further investigation for the discovery of a solution of the above problem was abandoned. However, in practice cases are met with where the employment of the two perpendicular loops is preferable to the use of one small revolving coil. One of these cases is that of aeroplanes on which it is often practically impossible to mount the small rotatable loops even if it is only of a diameter of 60 centimeters. As a matter of fact, when mounted inside the cockpit of the aeroplane they occupy very valuable space. When placed on the outside of the aeroplane, either above or below, they become a hindrance for navigation. An ideal solution to the problem is found by disposing the two loops in such a manner that one is fastened on to one of the wings of the aeroplane and the other is situated in the cockpit (see Fig. 1), the

110

two loops being connected with the radio-goniometer and an amplifier-detector.

The invention forming the subject matter of this application allows of the employment 5 of two perpendicular loops which are tuned to the wave length to be received, for the purpose of being used as a radio-goniometer.

To accomplish this end it is not necessary to use an individual condenser for each 10 loop, but rather a system of four condensers, (—C— 1, —C— 2, —C— 3, —C— 4,) disposed in a manner of a Wheatstone bridge as illustrated in Fig. 2. The two loops are connected between AB and CD. The four 15 condensers are connected mechanically by means of compensating gearing, or by any other suitable mechanical system, so that these condensers may be operated simultaneously indicated in Fig. 5 and at the same 20 time to the zero or to the 180 degree position. It can be readily seen that the resultant capacity for the coil connected at AB is:

$$25 \quad \frac{1}{\frac{1}{C_2} + \frac{1}{C_3}} + \frac{1}{\frac{1}{C_1} + \frac{1}{C_4}}$$

which reduces to

$$30 \quad \frac{C_1 C_2 C_3 + C_2 C_3 C_4 + C_3 C_4 C_1 + C_4 C_1 C_2}{(C_1 + C_2)(C_3 + C_4)}$$

while that for the loop connected between CD will be:

$$35 \quad \frac{1}{\frac{1}{C_1} + \frac{1}{C_2}} + \frac{1}{\frac{1}{C_3} + \frac{1}{C_4}},$$

which reduces to

$$40 \quad \frac{C_1 C_2 C_3 + C_2 C_3 C_4 + C_3 C_4 C_1 + C_4 C_1 C_2}{(C_1 + C_2)(C_3 + C_4)}$$

The ratio between the two capacities is:

$$45 \quad \frac{(C_1 + C_4)(C_2 + C_3)}{(C_1 + C_2)(C_3 + C_4)}$$

By the application of numerical examples it will be easy to find that this relationship comes invariably close to unity, provided the 50 four condensers are not unduly different from another. The two coils will be almost exactly tuned. The equation for this ratio shows that it will be sufficient for the two opposite condensers to be equal in order that 55 the resultant capacities may be alike.

Even if the capacities have thus been made practically alike it is an advantageous plan to make the resonance curves of the two loops as flat as feasible. In order to obtain 60 this end it is necessary that the two loops should consist of only one turn, or else of several turns in parallel, without any self-inductance coil being added in series except, it must be understood, the self-inductance 65 coil to be added to the smaller loop in order

to make it equal to the other one. It may even be a good plan to provide shunts for the self-inductance of these loops.

In this invention it is one of the objects not to provide two loop condensers that are 70 absolutely alike, but merely to provide condensers which differ a little from one another, in order to obtain with continuous wave and amplifiers the same results formerly to be realized only with crystal detector and damped wave receiving apparatus.

With such a condenser arrangement it is possible to use radio-goniometers either of the magnetic or of the electrostatic type. 80

The arrangement comprising four condensers may be further improved by the use of a balanced circuit consisting of a toroid-shaped winding, disposed in the manner indicated in Fig. 3, or better still as illustrated in Fig. 4, and the uni-control arrangement shown in Figure 5 may also be used in connection therewith. The magnetic actions between the different parts of this winding tend to equalize the currents in the diametrically opposite quadrants thereby tending to further diminish the effects of inequalities between the four condensers. 85

Having thus described my invention, what I claim is new and desire to secure by Letters Patent is:

1. In a radio-goniometer, a pair of loop aerials and means for tuning said loop aerials, said means consisting of a bridge circuit comprising a plurality of tuning elements forming the arms of said bridge circuit, each of said loop aerials being connected across a pair of opposite terminals of the bridge. 100

2. In a radio-goniometer, a pair of loop aerials and means for tuning said loop aerials, said means consisting of a bridge circuit comprising a plurality of condensers forming the arms of said bridge circuit, each of said loop aerials being connected across a pair of opposite terminals of the bridge. 105

3. In a radio-goniometer, a pair of loop aerials, a bridge circuit having each pair of opposite terminals connected to the terminals of one of said loops, said bridge circuit comprising a plurality of elements adapted to tune the loop aerials and means for simultaneously adjusting the tuning elements comprising said bridge circuit. 115

4. In a radio-goniometer, a pair of loop aerials, a bridge circuit having each pair of opposite terminals connected to the terminals of one of said loops, said bridge circuit comprising a condenser in each arm of said bridge adapted to tune the loop aerials and means for simultaneously adjusting all the condensers comprising said bridge circuit. 125

5. In a radio-goniometer, a pair of loop aerials, a bridge circuit having each pair of 130

- opposite terminals connected to the terminals of one of said loops, the arms of said bridge circuit each comprising an inductance and a capacity for tuning the loops.
- 5 6. In a radio-goniometer, a pair of angularly disposed loop aerials, a bridge circuit having each pair of opposite terminals connected to one of said loops, and substantially equal tuning elements in the arms of said bridge circuit simultaneously adjusted for obtaining syntony between the loops.
- 10 7. In a radio-goniometer, the combination with a pair of fixed loop aerials, of a bridge circuit having each pair of opposite terminals connected to one of said loops, and tuning elements in the arms of said bridge circuit, each arm comprising a capacity connected symmetrically with respect to an inductance.
- 15 8. In a radio-goniometer, two fixed loop aerials, a bridge circuit connected thereto for tuning said loops, capacity means for balancing the bridge circuit, additional means to further balance the bridge circuit, said additional means consisting of a plurality of toroidal-shaped inductance coils, and means for connecting said inductance coils to the bridge circuit.
9. In a radio-goniometer, the combination with two fixed loops located in planes at substantially right angles, of a bridge circuit associated therewith provided with a variable condenser in each of the bridge arms for tuning the bridge circuit, said fixed loops being connected to conjugate points of said bridge circuit whereby syntony is effected between the loops.
10. In a radio-goniometer, a loop aerial, a second loop aerial arranged at substantially right angles thereto, a bridge comprising four tuning elements, said loops being connected to conjugate points of the bridge circuit, and simultaneously operated means for varying the impedance of all said tuning elements.

ETTORE BELLINI.
